UNITED STATES PATENT OFFICE.

NICHOLAS MEYERS, OF BUFFALO, NEW YORK, ASSIGNOR TO PETER C. MEYERS, OF BUFFALO, NEW YORK.

SHEET-DELIVERY MECHANISM.

1,085,872.

Specification of Letters Patent.

Patented Feb. 3, 1914.

Application filed June 10, 1910. Serial No. 566,248.

To all whom it may concern:

Be it known that I, NICHOLAS MEYERS, a citizen of the United States, residing at Buffalo, in the county of Erie and State of New York, have invented new and useful Improvements in Sheet-Delivery Mechanism, of which the following is a specification:

This invention relates to a sheet delivery mechanism for printing presses and more particularly to a device of this character which is specially suited for small presses by which circular letters are printed.

It is the object of this invention to provide a delivery mechanism for this purpose which is simple in construction, reliable in operation and can be produced at comparatively low cost.

In the accompanying drawings consisting of 3 sheets, Figure 1 is a fragmentary elevation, partly in section, of a printing press equipped with my improved sheet delivery mechanism and showing the delivery gripper in its receiving position. Fig. 2 is a similar view of these parts but showing the delivery gripper in its discharging position. Fig. 3 is a perspective view of the delivery gripper. Fig. 4 is a cross section in line 4—4, Fig. 3. Fig. 5 is a fragmentary top plan view of the sheet delivery mechanism and the adjacent part of the printing press. Fig. 6 is a horizontal section in line 6—6, Fig. 1.

Similar letters of reference indicate corresponding parts throughout the several views.

The printing press shown in the drawings for exemplifying the application of my improved sheet delivery mechanism comprises a main frame A, a horizontally and longitudinally reciprocating bed B guided on the frame and adapted to support a chase of printing type or plates C on its upper side, an inking ribbon D extending over said printing surface for producing an impression of the same on the sheet E which is pressed downwardly on the same by any suitable means, and a roller e which is mounted transversely and horizontally on the bed at the front or delivery end thereof and upon which the surplus of the inking ribbon at one end is wound. Said roller is arranged a sufficient distance below the top or face of the type so as to provide a clear space above the roller in which the gripper

of the sheet delivery mechanism is free to 55 operate.

My improved sheet delivery mechanism which is associated with this printing press is constructed as follows: F represents a guideway having a horizontal lower part f which is arranged lengthwise and centrally below the printing bed and a forwardly and upwardly curved front part f¹ which has its upper end arranged centrally in front of where the front end of the type bed terminates its forward stroke while the lower end connects with the front end of the straight lower part f. This guideway is preferably constructed in the form of a flattened tube and provided in the outer or 65 convex side of its curved front part with a longitudinal slot g and on the upper side of its lower horizontal part with a longitudinal slot g¹. The upper and lower parts of the guideway are connected by upper and lower 70 brackets H, H¹ with the adjacent parts of the press frame, thereby forming a support 75 for the guideway.

Sliding in the guideway is a flexible shifting band I which is preferably of laminated 80 form and constructed of a plurality of superposed layers or strips of steel or similar material which has the necessary flexibility to adapt itself to the curved part of the guideway upon being moved lengthwise 85 therein and which is sufficiently rigid lengthwise, so that power may be transmitted by the same for actuating parts to be presently described.

A longitudinally reciprocating movement 90 may be imparted to the band by any suitable means but preferably by means of a horizontal longitudinal link i connected at its front end with the lower or rear end of the shifting band by a bolt i¹ and connected at 95 its lower end with a hanger J depending from the type bed.

To the upper or front end of the shifting band is secured a delivery gripper whereby the printed sheets are successively carried 100 off from the type bed and delivered upon a receiving table K arranged in front and below the front end of the type bed. This gripper is constructed as follows:—L, M represent the relatively movable and fixed 105 jaws of the gripper which are adapted to engage with opposite sides of the front edge of the printed sheet. The fixed jaw is ar-

ranged on the front end of a shank *N* which is secured at its rear end to a head *m* on the front or upper end of the shifting band, the shank, head and band being connected by a screw or rivet *n*, as shown in Figs. 1 and 5. The movable jaw is arranged on the front arm of a vertically swinging rock lever passing through corresponding ears *p* on the lever *o* and shank *N* and which is pivoted 10 on the shank by a transverse pin *o*¹ which is constantly turned in the direction for holding its jaw yieldingly in engagement with the fixed jaw by means of a spring *p*¹ surrounding the pivot pin *o*¹ and connected 15 at its opposite ends with the jaw lever and shank, respectively.

The fixed jaw is comparatively thin so as to be able to enter the narrow space between the top of the type chase and the front edge 20 of the sheet for engaging with the underside of the latter and the movable jaw is provided with a facing *q* of rubber or similar material so as to enable the same to obtain a firm hold on the top of the sheet. The rear parts of the shank and gripper lever are deflected outwardly so as to clear the guideway and ink roller but the jaws thereof are bent inwardly, so that when the same are at the 25 upper part of the guideway they are able to reach downwardly and engage with opposite sides of the front edge of the sheet, as shown in Fig. 1.

The gripper is moved alternately to the upper and lower ends of the curved part of the guideway by the reciprocating band and the actuating mechanism thereof. In its uppermost position the gripper faces rearwardly and is caused to engage with the front edge of the printed sheet while in its lowermost position the gripper faces forwardly and is caused to release the sheet, whereby the latter upon being withdrawn from the type bed and moved with the gripper from its upper to its lower position is reversed upside down and also fore and aft and then deposited on the receiving table.

The preferred means for causing the gripper to grasp and release the sheets is constructed as follows: *R* represents a tripping or shifting member having a main part *r* extending across the shank and lever of both gripper jaws at corresponding edges thereof and provided at its outer end with a foot or shoulder *s* adapted to bear against the outer side of the rear arm of the gripper lever and provided at its inner end with a heel or shoulder *t* which projects toward the underside of the shank of the fixed gripper jaw, a spring *u* connecting the foot with the gripper lever, an upper cam *w* secured to the upper end of the curved part of the guideway in the path of the heel *t* and a lower cam *w*¹ secured to the lower end of the curved part of the guideway in the path of said heel.

As the gripper approaches near to the front edge of the sheet on the type of the printing bed its heel *t* engages with the underside of the upper cam *w* thereby causing the gripper lever to be turned in the direction for moving the movable jaw away from the fixed jaw, as shown by dotted lines in Fig. 1. While in this open position the gripper in continuing its backward movement passes its lower fixed jaw underneath the printed sheet on the type and its upper movable jaw over the printed sheet. During the last part of the rearward movement of the gripper its heel *t* slips off the highest part of the upper cam, thereby permitting the spring *p*¹ to close the jaws of the gripper on the sheet and obtain a firm hold on the same. After the sheet has been thus grasped by the gripper the latter is moved downwardly into its lowered and reversed position, whereby the sheet is withdrawn from the type and reversed. During the initial part of the downward movement of the gripper its heel *t* rides over the upper side of the upper cam and is deflected outwardly without producing any effect, this being permitted by the spring *u* which connects the foot *s* with the gripper lever. During the last part of the downward movement of the gripper its heel *t* engages with the upper side of the lower cam *w*¹, as shown in full lines in Fig. 2, thereby opening the gripper and releasing the sheet which is now free to drop in a reversed position on the sheet receiving table. As the gripper moves upwardly away from the lower cam the movable jaw is again permitted to close against the fixed jaw, as shown by dotted lines in Fig. 2, but during the last part of its upward movement the gripper is again operated upon by the upper cam for causing the gripper to first open and then close for gripping the next printed sheet. Accidental displacement of the gripper opening the trip finger is prevented by means of a guide eye *r*¹ arranged on the rear arm of the gripper lever and receiving the main part *r* of said finger, as shown in Figs. 3 and 5.

While the gripper is moving back and forth from its upper to its lower position the head *N* moves through the outer slot *g* of the curved part of the guideway and the connection *i*¹ between the link *i* and the band *F* moves through the slot *g*¹ in the upper side of the lower straight part of the guideway.

During the operation of the machine the gripper always overhangs the front end of the type chase and ribbon roller in the foremost position of the bed. Inasmuch as the type chase or printing plates as well as the ink ribbon can only be conveniently removed in this foremost position of the bed in the press shown in the drawings, means must be provided for temporarily shifting the gripper 120

- per out of the way to permit of the removal of the type and ribbon and the replacement of the same. For this purpose the shank of the fixed gripper jaw is pivoted on the head ⁵ *m* and band *F* by the rivet *n*, so that the gripper as a whole can be turned laterally clear of the front end of the type and the ribbon, as shown by dotted lines in Fig. 5. After the type and ribbon have been ¹⁰ replaced the gripper may be again turned to its normal operative position shown in full lines in Fig. 5. This lateral movement of the gripper is limited and the same is held in its operative position by means of a ¹⁵ clamping screw *x* passing through an opening in the gripper head *m* and a concentric segmental slot *y* in the gripper shank and a nut *z* on the screw *x* bearing against the upper side of said shank.
- ²⁰ I claim as my invention:
1. A sheet delivery mechanism comprising a guideway having a vertically curved part, a flexible sheet metal shifting member reciprocating lengthwise in the guideway, and a gripper mounted on said shifting member and adapted to be reversed during its movement with said shifting member for reversing the sheet while the gripper holds the same.
  2. A sheet delivery mechanism comprising a guideway having a vertically curved part, a flexible sheet metal shifting member slidable lengthwise in the guideway, a gripper mounted on the front end of said shifting member and adapted to be reversed during its movement with said shifting member for reversing the sheet while held by the gripper, and means for actuating said shifting member comprising a reciprocating element, and a link connecting said reciprocating element with the rear end of the shifting member.
  3. A sheet delivery mechanism comprising a tubular guideway having a horizontal rear part which is provided with a longitudinal slot and a curved front part which is connected at its rear end with the front end of the rear part and is provided with a longitudinal slot, a flexible shifting member ³⁵ slidable lengthwise in said guideway, a gripper, a connection between said gripper and shifting member which moves lengthwise in the slot of the front part of the guide, a re-
  - ciprocating element, and a connection between said reciprocating element and the shifting member movable lengthwise relatively to the slotted rear part of the guideway.
  4. A sheet delivery mechanism comprising a shifting member, a gripper having relatively fixed and movable jaws, a shank carrying the fixed jaw and connected with said shifting member, a lever pivoted to said shank and carrying the movable jaw on its front arm, a spring for holding said jaws ⁶⁰ yieldingly in a closed position, a trip finger having an outer shoulder bearing against the outer side of the lever and an inner shoulder, a spring connecting the upper end of said finger with said lever, and a cam ⁶⁵ adapted to be engaged by the inner shoulder of the trip finger.
  5. A sheet delivery mechanism comprising a shifting member, a gripper having relatively fixed and movable jaws, a shank ⁷⁰ carrying the fixed jaw and connected with said shifting member, a lever pivoted to said shank and carrying the movable jaw on its front arm and having a guide eye, a spring for holding said jaws yieldingly in a closed ⁷⁵ position, a trip finger in said guide eye and having an outer shoulder bearing against the outer side of the lever and an inner shoulder, a spring connecting the upper end of said finger with said lever, and a cam ⁸⁰ adapted to be engaged by the inner shoulder of the trip finger.
  6. A sheet delivery mechanism comprising a movable support, a gripper having relatively fixed and movable jaws, a shank ⁸⁵ carrying said fixed jaw and pivoted on said support to swing transversely and provided with a segmental slot, a lever pivoted on the shank and carrying the movable jaw, and means for clamping said shank against ⁹⁰ turning on the support consisting of a bolt arranged on the support and passing through said slot, and a screw nut arranged on said bolt and bearing against said shank.
